(57) **CLAIM**

The ornamental design for a hyperspectral camera, as shown and described.

DESCRIPTION

FIG. 1 is a front, top perspective view of a hyperspectral camera showing my new design;

FIG. 2 is a front, bottom perspective view thereof;

FIG. 3 is a rear perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a left side view thereof; and,

FIG. 9 is a right side view thereof.

The broken lines depict portions of the hyperspectral camera that form no part of the claimed design.
